PACKAGING BOX

Joseph H. Vineberg, 257 Island Park Drive,
Ottawa, Ontario, Canada

Filed June 6, 1962, Ser. No. 200,422
1 Claim. (Cl. 229—23)

This invention relates to packaging boxes for use in the distribution and sale of various articles of commerce.

Box packaging in the retail field is a necessary procedure in the sale of many articles of merchandise but it constitutes a phase of merchandising which is subject to many well-recognized disadvantages. Many types of boxes, if they are to provide the required degree of protection for the packaged article, are relatively costly and thus indirectly increase the cost of the article. Boxes for certain articles, such as hats, shoes, and the like require formation from a relatively large amount of heavy paperboard and are thus quite costly to manufacture.

An object of the present invention is the provision of a box structure which may be manufactured at substantially reduced cost, which may be produced in collapsed condition and thus is subject to convenient storage in such condition; which may be readily and conveniently erected for reception of articles to be packaged therein; which may be manufactured at low cost while possessing fully adequate and satisfactory strength for protection of packaged articles; and which may have an inexpensive handle structure incorporated therewith for convenience of package carrying.

Another object of the invention is the provision of a box structure which may be employed by a manufacturer as an initial packaging means, which requires no repackaging by the retailer, and which is subject to more convenient packing of articles therein.

The invention will be described with reference to the accompanying drawing, in which:

FIGURE 1 is a perspective view of a box in accordance with the invention in erected form;

FIGURE 2 is a plan view of a blank employed in the formation of the box of FIGURE 1;

FIGURE 3 is a plan view of a second blank employed in the formation of the box of FIGURE 1;

FIGURE 4 is a perspective view of the box in partially erected form;

FIGURE 5 is a sectional elevation of a modified form of box in accordance with the invention;

FIGURE 6 is a plan view of a further form of box structure in non-erected condition;

FIGURE 7 is a perspective view of the box of FIGURE 6 in partially erected condition;

FIGURE 8 is a perspective view of a handle member for use with the box of FIGURES 6 and 7;

FIGURE 9 is a perspective view of still another modification of box structure in accordance with the invention;

FIGURE 10 is a sectional end elevation of the structure shown in FIGURE 9;

FIGURES 11 and 12 are plan views of blanks employed in the structure of FIGURE 9;

FIGURE 13 a partial elevation of the rear of the structure of FIGURE 9, and

FIGURE 14 is a section on line 14—14 of FIGURE 13.

Referring to FIGURES 1 to 4, 1 is a rectangular blank of flexible sheet material such as paper, cardboard or the like. The blank 1 has a bottom panel 2, side wall panels 3 and 4 extending from panel 2 and defined by fold lines 5, and top wall panels 6 and 7 extending from panels 3 and 4 and defined by fold lines 8. Each panel 3 and 4 is preferably provided with end flaps 9.

2

Top wall panel 6 has a handle flap 10 partially severed therefrom, such handle flap having a handhole 11 therein. Top wall panel 7 has a slit 12 therein arranged to receive handle flap 10 in the erected form of the box.

5 A second rectangular blank 13 of flexible sheet material such as employed for blank 1 is provided and comprises a bottom panel 14, side wall panels 15 and 16 extending from panel 14 and defined by fold lines 17, and top wall panels 18 and 19 extending from side wall panels 15 and 16 and defined by fold lines 20. Top wall panel 18 has a handle flap 21 with handhole 22 therein partially severed therefrom. Top wall panel 19 has a slit 23 arranged to receive flap 21 in the folded condition of the blank.

15 In erecting the box described, no adhesive or other fastening means are required. Blank 13 is placed on blank 1 with bottom wall panels 2 and 14 in superimposed relation and their free edges substantially coinciding with respective fold lines 5 and 17. The article to be packaged may now be placed on the superimposed panels 2 and 14, and the panels 15, 16, 18 and 19 folded to form a rectangular open-ended enclosure with top wall panels 18 and 19 in overlapped position and handle flap 21 projecting through slit 23.

20 Panels 3, 4, 6 and 7 are now folded to form a rectangular enclosure, side wall panels 3 and 4 thereby closing the open ends of the enclosure formed by blank 13. Top wall panels 6 and 7 are placed in overlapped position, handle flap 10 being first passed through the opening formed by formation of handle flap 21 and such flaps 10 and 21 placed in abutting relation. The flaps 10 and 21 are then passed through the slit 12.

25 The described handle structure not only forms a convenient handling means for the package but it also constitutes an effective retaining means for holding the box in erected, closed condition.

30 Referring to FIGURE 5, the box shown therein is quite similar in structure to that shown in FIGURES 1 to 4 but comprises three blanks instead of two. A rectangular blank 24 has a bottom wall panel 25, side wall panel 26, and top wall panels 28 and 29. Panel 28 has a handle flap 30 and panel 29 has a flap receiving slit 31. A pair of blanks 32 and 33 each have a flap 34 secured as by adhesive to the under surface of bottom wall panel 25. Blank 32 has a side wall panel 35 and a top wall panel 36. Blank 33 has a side wall panel 37 and a top wall panel 38. Panel 36 has a handle flap 39 and panel 38 a handle flap receiving slit 40. Each side wall 35 and 37 has end flaps 41. The box is erected in similar manner to the box of FIGURES 1 to 4.

35 Referring to FIGURES 6, 7 and 8, the box illustrated has a structure of three blanks secured together closely similar to that of FIGURE 5, although the resulting box has a substantially different shape. A blank 42 has a bottom wall panel 43, side wall panels 44 and 45, and top wall panels 46 and 47 each having a handle flap receiving slit 48. A pair of blanks 49 and 50 each have a flap 51 secured to outer surface of bottom panel 43. Blank 49 has an end wall panel 52 and a top wall panel 53. Blank 50 has an end wall panel 54 and a top wall panel 55. Each panel 52, 53, 54 and 55 are provided with edges flaps 56. Each panel 53 and 55 has a handle flap receiving slit 57 therein. Erection of the box is conducted in the manner previously described. In erected condition, the slits 48 and 57 are in registry.

40 A handle member 58 is preferably associated with the box described and comprises a blank having a doubled handle flap 59 provided with handhole 60 formed by 45 partially severing a tab 61 therefrom. Shoulders 62 extend substantially right angularly from flap 59. During 50 erection of the box, the flap 59 is passed through the

slits 43 and 57 with the shoulders 62 underlying the top wall panels 46, 47, 53 and 55.

Referring to FIGURES 9 to 14, the box shown comprises a blank 63 having a bottom wall panel 64, side wall panels 65, a top wall panel 66 extending from one side wall panel, a flap 66a extending from panel 65, and a top flap 67 extending from the other side wall panel 65. Flap 66a has a tab 68 partially severed therefrom.

A second blank 69 has a top wall panel 70, end wall panels 71, and a bottom wall panel section 72 extending from each end wall panel. Each panel 70, 71 and 72 is provided respective edge flaps 70a, 71a, and 72a. Top wall panel 70 has an opening 73 therein and one of the bottom wall panel sections 72 has a tab 74 partially severed therefrom.

In assembling the structure described, the top panel 70 of blank 69 is placed in superimposed relation to top panel 66 of blank 63. Flap 66a is folded over panel 70 and its tab 68 passed through opening 73 in panel 70 to secure the assembly in position. The remaining panels of blank 69 are now folded into wall forming position and tab 74 of one bottom wall panel 72 passed through a slit 75 in the other bottom wall panel 72 and also through a pair of slits 76 in bottom wall panel 64 to further secure the assembly in position. The structure is now substantially as shown in FIGURE 9, whereby one side wall panel 65 and its flap 67 constitute a closure means for the formed box.

It is proposed to employ a handle 58 such as shown in FIGURE 8 for the box structure of FIGURES 9 to 14. The handle flap 59 is adapted to be passed through a series of registering slits 77, 78, 79. Finally, in closing the box, the flap 67 is placed over panel 66 and the handle flap 59 passed through a slit 80 in flap 67.

It will be appreciated that the side wall opening of the box structure of FIGURES 9 to 14 is of great convenience in the packing therein of many types of articles.

It is contemplated that the structure of FIGURES 9 to 14 may be employed by a manufacturer in the packing of certain articles such as shoes and the like. A handle 58 may be supplied within the box and the retailer when selling the article, may simply associate the handle with the structure in the manner described and thus employ the box as the packaging means. Thus, no additional packing is required by the retailer.

A feature of the box structure described is that the various individual parts thereof may be produced in different colors to add to the attractiveness of the completed box. Printing on the box could, of course, be in

still another color. Thus, as many as four colors may be achieved in the box structure with a minimum of effort and expense.

I claim:

- 5 A box structure comprising a unitary blank of flexible material having a bottom wall panel, a pair of side wall panels extending from said bottom wall panel, and a top wall panel extending from each of said side wall panels, said top wall panels being foldable into overlapping relation over said bottom wall panel, a second unitary blank of flexible material having a bottom wall panel in unattached underlying relation to said first bottom wall panel, a pair of side wall panels extending from said second bottom wall panel, and a top wall panel extending 10 from each of said second side wall panels, said second top wall panels being foldable into overlapping relation with each other and with said first top wall panels, said bottom wall panels being of substantially equal size, and all of said side wall panels being of substantially equal 15 size, each of said last mentioned side wall panels having a flap at each end thereof foldable into unattached underlying relation with one of said first mentioned side wall panels, one of said top wall panels of each of said blanks having a handhole containing flap partially severed 20 therefrom, the other of said top wall panels of each of said blanks having a slit therein for reception of one of said handhole containing flaps, the handhole containing flap on one blank generally paralleling the longitudinal axis of the blank and the handhole containing flap on the 25 second blank being generally perpendicular to the longitudinal axis thereof so that the flaps are orientated in side by side relation when the top wall panels are orientated in perpendicular overlapping relation to each other, the handhole containing flap on the lowermost top wall panel 30 extending through three superimposed top wall panels with the other handhole containing flap extending through only one overlying top wall panel.
